TOBOGGAN OR THE LIKE

Irving M. Ziff, Culver City, Calif., assignor to Ziffco,
Culver City, Calif., a limited partnership in which
Ziffco, Inc., is a general partner

Filed Mar. 26, 1969, Ser. No. 16,449

Term of patent 14 years

Int. Cl. D21—03

U.S. Cl. D34—15

I claim:

The ornamental design for a toboggan or the like, as shown.
